United States Patent Office

Des. 220,874
Patented June 8, 1971

220,874

AMPHIBIOUS AND ROUGH TERRAIN VEHICLE

John A. Rogers and Frederick R. Bossard, Fort Dodge,
Iowa, assignors to Standard Engineering Co., Inc., Fort
Dodge, Iowa

Filed Feb. 12, 1970, Ser. No. 21,421

Term of patent 14 years

Int. Cl. D12—09

U.S. Cl. D14—3

Fig. 1

Fig. 2

FIG. 1 is a front perspective view of an amphibious and rough terrain vehicle showing our new design;

FIG. 2 is a top plan view thereof;

FIG. 3 is a front elevational view thereof;

FIG. 4 is a side elevational view thereof; and

FIG. 5 is a rear elevational view thereof.

We claim:

The ornamental design of an amphibious and rough terrain vehicle, substantially as shown.
